UNITED STATES PATENT OFFICE

146,946

DESIGN FOR A FIGURE TOY

Jeanette F. Mitchell and Susan S. Brown,
Portsmouth, Va.

Application October 28, 1946, Serial No. 134,320

Term of patent 3½ years

(Cl. D34—2)

To all whom it may concern:

Be it known that we, Jeanette F. Mitchell and Susan S. Brown, citizens of the United States, residing at Portsmouth, in the county of Norfolk and State of Virginia, have invented a new, original, and ornamental Design for a Figure Toy, of which the following is a specification, reference being had to the accompanying drawing, forming part thereof.

We claim:

The ornamental design for a figure toy, substantially as shown.

JEANETTE F. MITCHELL.
SUSAN S. BROWN.
